United States Patent Office

Des. 215,228

Patented Sept. 16, 1969

215,228

CANISTER SET

Jack Solomon, Brooklyn, N.Y., assignor to Pantry Queen Products Inc., Brooklyn, N.Y., a corporation of New York

Filed Sept. 16, 1968, Ser. No. 13,548

Term of patent 14 years

Int. Cl. D7—01

U.S. Cl. D44—6

FIG. 1.

FIG. 2.

FIG. 4.

FIG. 3.

FIG. 6.

FIG. 7.

FIG. 8.

FIG. 1 is a perspective view of a canister set showing my new design;

FIG. 2 is a top plan view thereof;

FIG. 3 is an elevational view thereof;

FIG. 4 is a front elevational view of one of the full size canister members;

FIG. 5 is a bottom plan view of the canister member shown in FIG. 4;

FIG. 6 is a side elevational view thereof;

FIG. 7 is a side elevational view of one of the half size canister members; and

FIG. 8 is a bottom plan view of the canister member shown in FIG. 7.

I claim:

The ornamental design for a canister set, substantially as shown.
